Des. 183,679

PAGE 3

Portions of the catamaran are stippled to indicate contrast.

I claim:

The ornamental design for an outboard catamaran, as shown and described.
